UNITED STATES PATENT OFFICE.

JAMES M. HARPER, OF CHICAGO, ILLINOIS.

DESIGN FOR A BASE FOR TOOL-SHARPENERS.

SPECIFICATION forming part of Design No. 32,157, dated January 30, 1900.

Application filed August 21, 1899. Serial No. 728,015. Term of patent 7 years.

To all whom it may concern:

Be it known that I, JAMES M. HARPER, a citizen of the United States, residing at Chicago, in the county of Cook and State of Illinois, 5 have invented and produced a new and original Design for a Base for Tool-Sharpener; and I do hereby declare the following to be a full, clear, and exact description of the same, reference being had to the accompanying drawings, forming a part of this specification, and in which—

Figure 1 is a plan view, and Fig. 2 a rear elevation.

This invention involves a design for the base 15 of a tool-sharpener for household uses; and it consists in the structural configuration hereinafter described and as illustrated in the accompanying drawings.

The supporting base or member is formed 20 with a horizontal portion 1, by which it is attached to a holding-block or other like support by means of a screw passing through a hole formed in such base, and with a vertical member 2, provided with a central hole or 25 orifice 3 for the reception of an attaching-

screw that secures a sharpener-disk in place to form a completed apparatus. Such vertical portion or member 2 is formed at one side with a round-ended angularly-arranged horn or guide 4 and at the opposite side with an 30 angularly-arranged horn or guide 5, the top surface of which is inclined slightly from the horizontal, as shown.

The essential feature of the design is the supporting-base formed by a horizontal portion and a vertical portion, such vertical portion having a central orifice and angularly-arranged horns at each side, the top surface of the one being slightly inclined from the horizontal. 35

I claim—

The design for the base of a tool-sharpener as herein shown and described.

In testimony whereof witness my hand this 14th day of August, 1899.

JAMES M. HARPER.

In presence of—

ROBERT BURNS,
M. H. HOLMES.
